BIS-(1-PIPERIDINO) ALKANES
Gordon Northrop Walker, Gillette, N.J., assignor to Ciba
Corporation, a corporation of Delaware
No Drawing. Filed Aug. 4, 1959, Ser. No. 831,459
10 Claims. (Cl. 260—293)

The present invention concerns bis-piperidino-alkane compounds. More particularly, it relates to compounds of the formula

Pi—Alk—Pi'

in which Alk represents an alkylene radical separating group Pi from group Pi' by four to twenty carbon atoms, and each of the groups Pi and Pi' stands for an amino-1-piperidino group, N-acylated derivatives, salts and quaternary ammonium compounds thereof.

The alkylene radical Alk, which separates the amino-1-piperidino radicals by from four to twenty carbon atoms, contains from four to twenty, more especially from six to fourteen, particularly from eight to twelve, primarily ten, carbon atoms, which may be arranged in a straight or in a branched chain. Such alkylene chains are, for example, 1,4-butylene, 1,5-pentylene, 1,6-hexylene, 1,7-heptylene, 1,8-octylene, 1,9-nonylene, 1,10-decylene, 1,11-undecylene, 1,12-dodecylene, 1,13-tridecylene, 1,14-tetradecylene, 1,15-pentadecylene, 1,16-hexadecylene, 1,17-heptadecylene, 1,18-octadecylene, 1,19-nonadecylene, 1,20-eicosylene, 1-methyl-1,5-pentylene, 3,3-dimethyl-1,5-pentylene, 3,4-dimethyl-1,6-hexylene, 4,4-dimethyl-1,7-heptylene, 2,7-dimethyl-1,8-octylene, 5-ethyl-1,9-nonylene, 1-methyl-1,10-decylene, 5,6-diethyl-1,10-decylene, 3,8-dimethyl-1,10-decylene and the like.

In the amino-1-piperidino moieties the amino group is located primarily in the 4-position of the piperidyl nucleus, but may also be attached to the 3-position of the ring.

The amino group of the amino-1-piperidino portion represents above all a primary amino group.

Amino may also stand for secondary amino, particularly N-lower alkyl-amino, e.g. N-methylamino, N-ethylamino, N-n-propylamino, N-isopropylamino and the like, N-carbocyclic arylamino, such as N-monocyclic carbocyclic aryl-amino, e.g. N-phenylamino and the like, or N-bicyclic carbocyclic aryl-amino, e.g. N-1-naphthyl-amino or N-2-naphthyl-amino and the like, or N-carbocyclic aryl-lower alkyl-amino, such as N-monocyclic carbocyclic aryl-lower alkyl-amino, e.g. N-benzylamino, N-1-phenylethylamino or N-2-phenylethyl-amino and the like, or bicyclic carbocyclic aryl-lower alkyl-amino, e.g. N-1-naphthyl-methylamino and the like.

Also included as amino groups are tertiary amino groups, such as, for example, N,N-di-lower alkyl-amino, e.g. N,N-dimethylamino, N-ethyl-N-methyl-amino, N,N-diethylamino, N,N-dipropylamino or N,N-di-isopropylamino and the like, N-lower alkyl-N-carbocyclic aryl-lower alkyl-amino, e.g. N-benzyl-N-methyl-amino or N-methyl-N-(2-phenylethyl)-amino and the like, or N-lower alkyl-N-lower cycloalkyl-amino, e.g. N-cyclopentyl-N-methyl-amino or N-cyclohexyl-N-methyl-amino and the like. Other tertiary amino groups are, for example, N,N-alkylene-imino groups, in which alkylene contains preferably from four to eight carbon atoms, e.g. 1-pyrrolidino, 2-methyl-1-pyrrolidino, 1-piperidino, 2-methyl-1-piperidino, 3-methyl-1-piperidino, 4-methyl-1-piperidino, 3-hydroxy-1-piperidino, 3-acetoxy-1-piperidino, 3-hydroxy-methyl-1-piperidino, N,N-1-hexamethyleneimino, N,N-1-heptamethyleneimino and the like, N,N-lower oxa-alkyleneimino, in which alkylene contains preferably four carbon atoms, e.g. morpholino, or N,N-lower aza-alkyleneimino, in which alkylene contains preferably four carbon atoms, e.g. piperazino, 4-methyl-piperazino, 4-benzyl-

2

piperazino, 4-(2-hydroxyethyl)-piperazino, 4-(2-acetoxyethyl)-piperazino and the like.

N-acyl-amino may also represent the amino group of the amino-1-piperidyl portion of the bis-(amino-1-piperidino)-alkanes of this invention. Acyl represents primarily the acyl radical of organic carboxylic acids. Such acids are, for example, aliphatic carboxylic acids, such as carbonic acids, especially O-lower alkyl-carbonic acids, e.g. O-methyl-carbonic or O-ethyl-carbonic acid and the like, O-carbocyclic aryl-lower alkyl-carbonic acids, e.g. O-benzyl-carbonic acid and the like, lower alkane carboxylic acids, which may contain other functional groups, e.g. formic, acetic, propionic, butyric, pivalic or trifluoroacetic acid and the like, carbocyclic aryl carboxylic acids, which may contain additional substituents, such as monocyclic carbocyclic aryl carboxylic acids, e.g. benzoic acid and the like, or carbocyclic aryl-lower alkane carboxylic acids, which may contain other groups, such as monocyclic carbocyclic aryl-lower alkanoic acids, e.g. phenylacetic, or 3-phenyl-propionic acid and the like, or other organic carboxylic acids.

The piperidine nucleus of the amino-1-piperidino group is preferably unsubstituted, or may contain one or more than one additional substituent, which may be attached to any of the positions available for substitution in the amino-1-piperidino nucleus. Such substituents are particularly lower alkyl, e.g. methyl or ethyl and the like, halogen, e.g. fluorine, chlorine or bromine and the like, lower alkoxy, e.g. methoxy or ethoxy and the like, or other substituents.

Although the two amino-1-piperidino groups Pi and Pi', connected through the alkylene radical, may be of different nature, they are preferably identical.

Salts of the compounds of this invention are particularly therapeutically acceptable acid addition salts with inorganic acids, such as mineral acids, e.g. hydrochloric, hydrobromic, sulfuric or phosphoric acids and the like, with organic carboxylic acids, e.g. formic, acetic, propionic, glycolic, lactic, pyruvic, malonic, succinic, maleic, hydroxymaleic, dihydromaleic, fumaric, malic, tartaric, citric, benzoic, cinnamic, mandelic, salicyclic, 4-amino-salicylic, 2-phenoxybenzoic or 2-acetoxybenzoic, and the like, or with organic sulfonic acids, e.g. methane sulfonic, ethane sulfonic or 2-hydroxyethane sulfonic acids. Salts, which are primarily used for identification purposes, are particularly those with acidic organic nitro compounds, e.g. picric, picrolonic or flavianic acid, or with metal complex acids, e.g. phosphotungstic, phosphomolybdic, chloroplatinic or Reinecke acid. Mono-, more particularly poly-, such as bis- or tetra-salts may be formed, depending on the procedure used for the preparation of the salts and/or the number of salt-forming groups present.

Quaternary ammonium derivatives of the compounds of this invention are particularly those with reactive esters formed by hydroxylated compounds and strong acids, particularly mineral acids, e.g. hydrochloric, hydrobromic or hydroiodic acid and the like, or strong organic sulfonic acids, e.g. methane sulfonic, ethane sulfonic or 2-hydroxyethane sulfonic acid and the like. Such esters are, for example, lower alkyl halides, e.g. methyl, ethyl, n-propyl or isopropyl chloride, bromide or iodide and the like, lower alkyl lower alkane sulfonates, e.g. methyl or ethyl methane or ethane sulfonate and the like, or lower alkyl lower hydroxy-alkane sulfonate, e.g. methyl 2-hydroxyethane sulfonate. Also included as quaternary ammonium compounds are the quaternary ammonium hydroxides, and the salts obtained by reacting the latter with inorganic, or more particularly with organic acids, such as with those described hereinbefore as being suitable for the preparation of acid addition salts. Mono- or poly-quaternary ammonium compounds may be formed, depending

on the procedure used for their formation and/or the number of tertiary amino groups present in the molecule.

The compounds may be in the form of mixtures of racemates, which may be separated into single racemates, or in the form of racemates, which may be resolved into the antipodes.

The compounds of the present invention have considerable bacteriostatic and bactericidal effects and may, therefore, be used to prevent the propagation and possibly to exterminate bacteria in an animal or human host, without noticeable adverse effects to the latter. Thus, the previously-described compounds and their salts show bacteriostatic and bactericidal activities against streptococci, such as *Streptococcus pyogenes*, and staphylococci, such as *Staphylococcus aureus*, and may, therefore, be used as bacteriostatic and bactericidal agents to prevent and/or combat infections of such bacteria in animals or humans. Particularly good bacteriostatic and bactericidal effects are shown by compounds of the formula

in which Alk' represents an alkylene radical containing from six to fourteen carbon atoms and separating the two groups Pi_1 by four to fourteen carbon atoms, and Pi_1 represents a 4-amino-1-piperidino group, and therapeutically acceptable acid addition salts thereof. This group may be represented by compounds of the formula

in which Alk'' represents a lower alkylene radical containing from eight to twelve carbon atoms and separating the two 4-amino-1-piperidino groups by the same number of carbon atoms, and their addition salts with mineral acids, e.g. hydrochloric, sulfuric or phosphoric acid, lower alkane carboxylic acids, e.g. acetic or propionic acid, lower alkane dicarboxylic acids, e.g. maleic acid, lower hydroxy-alkane dicarboxylic acids, e.g. tartaric acid, or lower hydroxy-alkane tricarboxylic acids, e.g. citric acid. This group of compounds may be represented by 1,10-bis-(4-amino-1-piperidino)-decane of the formula

and the salts, particularly salts with the above-mentioned monobasic and dibasic acids.

The new compounds of this invention may be used as medicaments in the form of pharmaceutical preparations, which contain the new bis-(amino-1-piperidino)-alkane compounds or their salts, especially their pharmacologically compatible acid addition salts, in admixture with a pharmaceutical organic or inorganic, solid or liquid carrier suitable for enteral, parenteral or topical administration. For making up the preparations there may be employed substances, which do not react with the new compounds, such as water, gelatine, lactose, starches, stearic acid, magnesium stearate, stearyl alcohol, talc, vegetable oils, benzyl alcohols, gums, propylene glycol, polyalkylene glycols or any other known carrier for medicaments. The pharmaceutical preparations may be in solid form, for example, as capsules, tablets or dragees and the like, in liquid form, for example, as solutions, e.g. isotonic saline solutions, or as suspensions, emulsions or creams and the like. If desired, they may contain auxiliary substances such as preserving, stabilizing, wetting or emulsifying agents, salts for varying the osmotic pressure or buffers, and the like. They may also contain, in combination, other therapeutically useful substances.

Advantageously the compounds of the present invention may be prepared by treating compounds of the formula

in which Alk has the above-given meaning, each of the radicals Py and Py' represents an amino-1-pyridinium group (amino having the previously-given meaning), and

5 An stands for the anion of an acid, with a reducing reagent, and, if desired, converting a primary or a secondary amino group in a resulting compound into a secondary or a tertiary amino, or, if desired, acylating a resulting compound, containing primary or secondary amino groups, and/or, if desired, hydrolyze compounds containing N -acyl groups, and/or, if desired, converting a resulting salt into the free base, and/or, if desired, converting a free base into its salts, and/or, if desired, converting in a resulting compound tertiary amino groups into quaternary ammonium groups, while temporarily protecting any primary or secondary amino groups, and/or, if desired, separating resulting mixtures of racemates into single racemates, and/or, if desired, resolving resulting racemates into antipodes.

10 In the above formula, depicting the starting materials, An stands primarily for the anion of a strong inorganic acid, such as a mineral acid, particularly a hydrohalic acid, especially hydrobromic acid, or of a strong organic sulfonic acid, such as a monocyclic carbocyclic aryl sulfonic acid, particularly p-toluene sulfonic acid. Anions of other inorganic or organic acids may also be conceivable, whereby anions of di-basic acids, such as, for example, sulfuric or tartaric acid may satisfy two positive pyridinium ions.

15 Reducing reagents capable of converting the bis-(amino-1-pyridinium)-alkane compounds into the desired bis-(amino-1-piperidino)-alkanes are primarily hydrides, especially borohydrides, such as alkali metal borohydride, e.g. lithium borohydride, sodium borohydride or potassium borohydride, alkaline earth metal borohydrides, e.g. calcium borohydride, strontium borohydride or barium borohydride, or alkali metal tri-lower alkoxy-borohydrides, e.g. sodium trimethoxy-borohydride. Alkali metal tri-lower alkoxy-aluminumhydrides, e.g. lithium tri-propoxy-aluminumhydride, may also be used as reducing agents. If desired, these reagents may be used together with an activator, such as, for example, aluminum chloride and the like. Solvents used in the reaction are, for example, lower alkanols, e.g. methanol or ethanol, or any other solvent compatible with the above-mentioned metal hydride compounds. The reaction may be carried out under cooling or at room temperature, and, if necessary, may be completed at an elevated temperature. If desired, it may be performed in the atmosphere of an inert gas, e.g. nitrogen.

20 Another reducing reagent capable of converting bis-(amino-1-pyridinium)-alkane compounds into the corresponding amino-1-piperidino derivatives, may be catalytically activated hydrogen, whereby the catalyst contains a metal of the eighth group of the periodic system, such as platinum or palladium; preferred catalysts are, for example, platinum oxide and palladium on charcoal. This hydrogenation may be carried out in the presence of a solvent, such as a lower alcanoic acid, e.g. acetic acid, 25 or a lower alkanol, e.g. methanol or ethanol, and the like; it may be performed under atmospheric or increased pressure, and, if desired, at an elevated temperature.

25 Nascent hydrogen, such as generated by a metal or a metal amalgam in the presence of a hydrogen donor, may also be used in the above-described reduction procedure; zinc in the presence of acetic acid or aluminum amalgam in the presence of a moist ether, e.g. tetrahydrofuran, are examples of sources of nascent hydrogen capable of performing the desired reaction.

30 The resulting bis(amino-1-piperidino)-alkanes may be isolated according to conventional methods; for example, an alcoholic solvent used in the metal hydride reduction may be evaporated, the residue suspended in a small amount of water and salted out into a supernatant, only partially water-miscible solvent, e.g. ether, by adding, for example, a solid carbonate, e.g. sodium or potassium carbonate, or an alkali metal halide, e.g. sodium chloride. The separated and dried organic, e.g. ether, phase may 35 be evaporated and the liquid may be decanted from a

residue after standing. The resulting free base may be purified by distillation, for example, in a molecular still, or, more advantageously, by conversion into a salt or into another derivative thereof, which may be further purified, for example, by recrystallization, if desired, in the presence of an adsorbent, e.g. charcoal, diatomaceous earth and the like.

The bis-amino-1-pyridinium-alkane compounds of the previously-given formula, which are used as the starting materials, are known or, if new, may be prepared according to the procedures used for the known compounds. They may be prepared, for example, by reacting two mols of an amino-pyridine compound with one mole of a reactive ester formed by a dihydroxy-alkane, in which the two hydroxyl groups are separated by at least four carbon atoms, and a strong inorganic acid, such as a mineral acid, particularly a hydrohalic acid, e.g. hydrobromic acid, or a strong organic sulfonic acid, such as a monocyclic carbocyclic aryl sulfonic acid, e.g. p-toluene sulfonic acid. The reaction may be carried out in the presence of an inert solvent, such as, for example, a carbocyclic aryl hydrocarbon, e.g. benzene, toluene or xylene, a high-boiling aliphatic hydrocarbon, e.g. hexane and the like, a lower alkanone, e.g. 2-butanone, or a lower alkanol, e.g. isopropanol. It is advantageously performed at an elevated temperature, preferably at the boiling temperature of the solvent.

Particularly useful as starting materials are compounds of the formula

in which Alk' represents an alkylene radical containing from six to fourteen carbon atoms and separating the two groups Py₁ by four to fourteen carbon atoms, and in which Py₁ represents a 4-amino-1-pyridinium and Hal stands for the anion of a hydrohalic acid. This group of starting materials may be represented by compounds of the formula

in which Alk'' represents an alkylene radical containing from eight to twelve carbon atoms and separating the two 4-amino-1-pyridinium groups by the same number of carbon atoms.

In the compounds resulting from the above-described procedure, primary or secondary amino groups may be converted into secondary or tertiary amino groups according to conventional methods. For example, compounds with primary amino groups may be treated with an aldehyde to form so-called Schiff bases, which upon reduction (for example, with sodium borohydride) yield compounds containing secondary amino groups. Such groups may also be obtained by reducing in N-acylated amino groups the amido into a methylene-amino group; the reduction may be carried out, for example, by treatment with an alkali metal aluminum hydride, e.g. lithium aluminum hydride, in an inert solvent, e.g. ether, whereby it may be advantageous to use an activator, such as aluminum chloride. The reduction of amides into amino groups is also suitable for the preparation of tertiary amino groups; upon treatment of an N-acylated secondary amino group with aluminum hydride, the tertiary amino group may be formed.

Tertiary, as well as secondary, amino groups may be formed from primary amino groups, for example, by treatment of the amino compounds with catalytically activated hydrogen in the presence of an aldehyde or a ketone. A catalyst contains a metal of the eighth group of the periodic system, such as palladium (palladium on charcoal), platinum (platinum oxide or platinum black) or nickel (Raney nickel) and the like; hydrogen may be applied under atmospheric, as well as under increased pressure. Any aldehyde or ketone compound suitable in

the formation of the previously-known secondary or tertiary amino groups may be used; for example the use of formaldehyde in the above reaction furnishes methyl groups, whereas acetone yields isopropyl groups.

- 5 The formation of secondary and tertiary amino groups from primary or secondary amino groups may also be achieved by treatment of the latter with esters, formed by hydroxylated compounds and strong acids, particularly hydrohalic acids; this reaction may be carried out 10 according to known procedures, such as, for example, according to the conditions used for the alkylation of primary and secondary amino groups with lower alkyl halides, e.g. methyl, ethyl, n-propyl or isopropyl chloride, bromide or iodide and the like.
- 15 Compounds, prepared according to the procedure of this invention, which contain primary or secondary amino groups, may be converted into acylated derivatives according to procedures used for the preparation of nitrogen-acylated derivatives. N-acylation may be carried out, for example, by treating the amino compound with a reactive functional derivative of one of the carboxylic acids mentioned hereinbefore, such as a halide, e.g. chloride, or an anhydride. The reaction may be carried out according to known procedures, for example, in the absence 20 or presence of a condensing reagent, such as a liquid organic base, for example, a tri-lower alkyl-amine, e.g. trimethylamine or triethylamine, or preferably a pyridine derivative, e.g. pyridine or collidine, particularly if an anhydride, e.g. acetic acid anhydride is used. Solvents 25 are anhydrous inert organic solvents, such as, for example, lower aliphatic ketones, e.g. acetone. Liquid basic condensation reagents, such as, for example, pyridine or collidine, may simultaneously serve as solvents. A liquid acylation reagent, such as, for example, acetic acid anhydride, may be used without an additional solvent. Depending on the number of available primary or secondary amino groups, the conditions of the reaction, and/or the molar ratios of the reactants, mono- or poly-acylated products may be obtained.
- 30 40 N-acylated derivatives may be converted into non-acylated compounds, for example, by acidic or basic hydrolysis. Particularly susceptible to hydrolytic cleavage are N-acylated amino compounds, in which the acyl group is derived from an O-lower alkyl-carbonic acid, e.g. O-methyl-carbonic or O-ethyl carbonic acid, or a polyhalogeno-lower alkane carboxylic acid, e.g. trifluoroacetic acid. Certain N-acylated amino groups may also be converted to non-acylated amino groups by hydrogenolysis; for example, compounds containing N-acyl-amino groups, in which acyl represents the acyl radical of an O-benzyl-carbonic, e.g. O-benzyl-carbonic acid, may be treated with hydrogen in the presence of a catalyst, such as palladium on charcoal, to cleave the N-acylated amino group.
- 35 45 50 55 Compounds of the present invention, which contain N-acyl-amino groups, particularly those which are easily cleaved by hydrolysis or hydrogenolysis, are, therefore, particularly suitable as intermediary compounds. Thus, reactions on compounds containing N-acylated amino 60 65 70 groups may be carried out, which otherwise would affect free primary or secondary amino groups; the temporary protection of the latter by way of removable acyl groups makes such reactions possible. After completion of the latter, compounds containing N-acylated groups may then be reconverted into compounds containing free primary or secondary amino groups. Acylation and deacylation may be carried out according to the previously-described or analogous procedures.
- The compounds of this invention may be obtained in 75 the form of free bases or as the salts thereof. A salt may be converted into the free base, for example, by reacting the former with an alkaline, particularly an aqueous alkaline, reagent, such as an alkali metal hydroxide, e.g. lithium, sodium or potassium hydroxide, an alkali metal carbonate, e.g. sodium or potassium carbonate or hydro-

gen carbonate, or ammonia. A free base may be converted into its therapeutically useful acid addition salts by reacting the free base with one of the inorganic or organic acids outlined hereinbefore; salt formation may be carried out, for example, by treating a solution of the free base in a solvent, such as a lower alkanol, e.g. methanol, ethanol, n-propanol or isopropanol and the like, or other suitable solvents with the acids or a solution thereof and isolating the resulting salt, for example, by adding another solvent, such as an ether, e.g. diethylether, and thus precipitating the salt, or by any other standard procedure. The salts (mono- or poly-salts) may also be obtained as the hemihydrates, monohydrates, sesquihydrates or polyhydrates depending on the conditions used in the formation of the salts.

Quaternary ammonium compounds may be formed from the compounds of this invention. Prior to quaternization, groups, such as primary or secondary amino groups, may temporarily be protected, for example, by easily removable acyl groups, such as those shown hereinbefore. The quaternization reaction may be carried out, for example, by treating the free base with an ester formed by a hydroxylated compound and a strong inorganic or organic acid. Hydroxylated compounds are primarily lower alkanols containing from one to seven carbon atoms, and esters thereof are more especially those with mineral acids, such as hydrohalic acids, e.g. hydrochloric, hydrobromic or hydriodic acid, or with organic sulfonic acids, such as lower alkane sulfonic acids, e.g. methane, ethane or 2-hydroxy-ethane sulfonic acid and the like. Such esters are, for example, lower alkyl halides, e.g. methyl, ethyl, n-propyl or isopropyl chloride, bromide or iodide and the like, or lower alkyl lower alkane sulfonates, e.g. methyl or ethyl methane sulfonate, ethane sulfonate or 2-hydroxy-ethane sulfonate. The reaction may be performed advantageously in the presence of a solvent, such as a lower alkanol, e.g. methanol, ethanol, propanol, isopropanol, butanol or pentanol, a lower alkanone, e.g. acetone or methyl ethyl ketone, or an organic acid amide, e.g. formamide or dimethylformamide, if necessary, at an elevated temperature, and/or in a closed vessel under pressure.

Quaternary ammonium compounds obtained may be converted into the corresponding quaternary ammonium hydroxides, for example, by reacting a quaternary ammonium halide with silver oxide, or a quaternary ammonium sulfate with barium hydroxide, by treating a quaternary ammonium salt with an anion exchanger, or by electrodialysis. From a resulting quaternary ammonium hydroxide there may be prepared therapeutically suitable quaternary ammonium salts by reacting the former with an acid, for example, with one of those described hereinbefore as being suitable for the preparation of the acid addition salts. A quaternary ammonium compound may also be converted directly into another quaternary ammonium salt without forming the quaternary ammonium hydroxide; for example, a quaternary ammonium iodide may be reacted with freshly prepared silver chloride to yield the quaternary ammonium chloride, or a quaternary ammonium iodide may be converted into the corresponding chloride by treatment with hydrochloric acid in anhydrous methanol. Quaternary ammonium compounds may also crystallize as hydrates, e.g. hemihydrates, monohydrates, sesquihydrates or polyhydrates.

The new compounds of this invention may be obtained as mixtures of racemates, which mixtures may be separated into the individual racemates on the basis of physico-chemical differences, such as solubility; such separation may be carried out, for example, by fractionated crystallization or distillation.

The racemates of the compounds of this invention may be resolved into the optically active d- and l-forms according to procedures known for the resolution of racemic compounds. For example, the free base of a racemic d,l-compound may be dissolved in a solvent, such as, for

example, a lower alkanol, e.g. methanol or ethanol, and one of the optically active forms of an acid containing an asymmetric carbon atom, or a solution thereof, for example, in the same lower alkanol or in another solvent may then be added, whereupon a salt can be isolated, which is formed by the optically active acid with one of the optically active form of the base. Especially useful as optically active forms of salt-forming acids having an asymmetric carbon atom are D- and L-tartaric acid; the optically active forms of malic, mandelic, camphor sulfonic or quinic acid may also be employed. From resulting salts, the free and optically active base may be obtained according to processes known for the conversion of a salt into a base, for example, as outlined hereinbefore. An optically active base may be converted into acid addition salts with one of the acids mentioned hereinbefore, or may be converted into other derivatives thereof. Optically active forms may also be isolated by biochemical methods.

The invention also comprises any modification of the process wherein a compound obtainable as an intermediate at any stage of the process is used as starting material and the remaining step(s) of the process is(are) carried out, as well as any new intermediates.

In the process of this invention such starting materials are preferably used which lead to final products mentioned in the beginning as preferred embodiments of the invention.

The following examples are intended to illustrate the invention and are not to be construed as being limitations thereon. Temperatures are given in degrees centigrade.

Example 1

A solution of 31.1 g. of 1,10-bis-(4-amino-1-pyridinium)-decane dibromide in about 500 ml. of methanol is treated with a large excess of sodium borohydride (a total of about 150 g.) in portions and over a period of several hours. At the beginning, the reaction proceeds exothermically and causes some evaporation of the methanol, which is replenished. After the initial exothermic reaction subsides, the reaction mixture is heated on the steam bath; additional sodium borohydride is added while heating. The solvent is then allowed to evaporate until a thick suspension is formed, which is cooled and treated with 150 ml. of water. Several hundred grams of potassium carbonate is added, and the organic material is extracted with three portions of ether (a total of about 2500 ml.). The ether solution is dried over potassium carbonate, filtered and evaporated. The residue is allowed to stand for several days; the liquid portion, representing the 1,10-bis-(4-amino-1-piperidino)-decane, is decanted from the solid phase.

It is converted into the salt as follows: A solution of the base in ethanol is treated with an excess of dry hydrogen chloride, the precipitate is filtered off, washed with ethanol (yield: about 5 g.) and recrystallized from the same solvent yielding the 1,10-bis-(4-amino-1-piperidino)-decane tetrahydrochloride, M.P. 285°. The hydrogen chloride may be replaced by other acids, such as, for example, sulfuric, phosphoric, maleic, tartaric or citric acid and the like may be used as salt-forming acids, whereupon the corresponding sulfate, phosphate, maleate, tartrate or citrate and the like of 1,10-bis-(4-amino-1-piperidino)-decane may be isolated.

The starting material may be prepared as follows: A mixture of 15.5 g. of 2-aminopyridine, 25 g. of 1,10-dibromodecane and 250 ml. of toluene is refluxed for five hours. A crystalline, tan precipitate is formed, the reaction mixture is cooled and the solid material is collected, dried and recrystallized from ethanol to give the colorless 1,10-bis-(4-amino-1-pyridinium)-decane dibromide, M.P. 247°; yield of crude material; 41.4 g.

Example 2

The 1,4-bis-(4-amino-1-piperidino)-butane tetrahydrochloride, M.P. 305°, may be prepared by reacting 1,4-di-

bromobutane with 4-amino-pyridine, reducing a methanol solution of the resulting 1,4-bis-(4-amino-1-pyridinium)-butane dibromide, M.P. 275°, with sodium borohydride and converting the resulting free base into the salt according to the procedure described in Example 1.

Example 3

Treatment of 1,6-bis-(4-amino-1-pyridinium)-hexane dibromide, M.P. 305°, which may be prepared by reacting 1,6-dibromohexane with 4-amino-pyridine, with sodium borohydride in the presence of ethanol gives rise to the formation of 1,6-bis-(4-amino-1-piperidino)-hexane, identified as the tetrahydrochloride melting at 204°.

Example 4

A solution of 1,8-dibromo-octane and 4-amino-pyridine, when refluxed according to the procedure of Example 1, yields the 1,8-bis-(4-amino-1-pyridinium)-octane dibromide, M.P. 302°, which is reduced to the desired 1,8-bis-(4-amino-1-piperidino)-octane by treatment of a methanol solution of the former with sodium borohydride, according to the process described in Example 1; the free base is converted to the tetrahydrochloride, M.P. 306°, by treatment with hydrogen chloride.

Example 5

The reduction of 1,9-bis-(4-amino-1-pyridinium)-nonane dibromide, M.P. 222° (prepared from 1,9-dibromononane and 4-amino-pyridine), with sodium borohydride in the presence of methanol yields the 1,9-bis-(4-amino-piperidino)-nonane, characterized as the tetrahydrochloride, M.P. 321°. The reactions are carried out according to the procedure of Example 1.

Example 6

The 1,12-bis-(4-amino-1-piperidino)-dodecane may be prepared by treating a methanol solution of 1,12-bis-(4-amino-1-pyridinium)-dodecane dibromide, M.P. 210°, with sodium borohydride according to the procedure described in Example 1; the free base may be characterized as its tetrahydrochloride.

The starting material may be prepared as previously shown, i.e. by refluxing a toluene solution of 1,12-dibromododecane with 4-amino-pyridine.

Example 7

1,8-dibromo-octane and 4-amino-2-methyl-pyridine, when refluxed in a toluene solution, yields the 1,8-bis-(4-amino-2-methyl-pyridinium)-octane dibromide, M.P. 308°, which is reduced by treatment of methanol solution thereof with sodium borohydride, to yield the desired 1,8-bis-(4-amino-2-methyl-piperidino)-octane, characterized as the tetrahydrochloride.

Example 8

The reaction of a methanol solution of 1,10-bis-(3-amino-1-pyridinium)-decane dibromide, which is prepared by reacting 3-amino-pyridine with 1,10-dibromodecane in toluene, with hydrogen in the presence of platinum yields the desired 1,10-bis-(3-amino-1-piperidino)-decane, identified as its tetrahydrochloride.

Example 9

The reduction of 1,9-bis-(4-amino-2-methyl-1-pyridinium)-nonane dibromide, M.P. 277°, with sodium borohydride according to the method described in Example 1 yields the 1,9-bis-(4-amino-2-methyl-piperidino)-nonane, characterized as the tetrahydrochloride. The starting material is prepared by refluxing a toluene solution of 1,9-dibromononane and 4-amino-2-methyl-pyridine.

Example 10

Upon treatment of 1,10-dibromo-undecane with 4-amino-pyridine in refluxing toluene the 1,10-bis-(4-amino-1-pyridinium)-undecane dibromide, M.P. 200°, can be prepared, which, upon treatment of a methanol solution

thereof with sodium borohydride according to the procedure of Example 1 yields the 1,10-bis-(4-amino-1-piperidino)-undecane; the free base may be converted and characterized as the tetrahydrochloride.

Example 11

Treatment of an ethanol solution of 1,10-bis-(4-amino-1-piperidino)-decane with hydrogen in the presence of palladium on charcoal and an excess of an aqueous solution of formaldehyde results in the formation of the 1,10-bis-(4-dimethylamino-1-piperidino)-decane.

Example 12

Upon reacting the 1,10-bis-(4-amino-1-piperidino)-decane with trifluoroacetic acid anhydride in the presence of pyridine the 1,10-bis-[4-(N-trifluoroacetylamino)-1-piperidino]-decane may be obtained, which, when treated with methyl iodide, yields the 1,10-bis-[4-(N-trifluoroacetylamino)-1-piperidinium]-decane di-iodide. The N-trifluoroacetylamino groups of the resulting compound may be hydrolyzed by treatment with sodium hydroxide to yield the desired 1,10-bis-(4-amino-1-piperidinium)-decane di-iodide.

The compounds of the present invention may also be prepared according to other procedures. For example, in bis-1-piperidino-alkane compounds, in which the piperidino groups contain functional substituents capable of being converted into amino groups of the previously-mentioned type, such groups may be converted into amino groups, and, if desired, the optional steps may be carried out.

Functional groups which may be converted into amino groups are primarily carboxyl groups, or particularly functional derivatives thereof. Functional derivatives of carboxyl groups are primarily their esters with lower alkanols, e.g. methanol or ethanol, which are capable of being converted via hydrazides into azides; under the conditions of the Curtius reaction, such carboxylic acid azides are rearranged to the isocyanates, which, upon hydrolysis, yield the desired amino group. The azide of the carboxyl group may also be obtained directly from the carboxyl group by treatment with hydrazoic acid; this reaction may be carried out in the presence of sulfuric acid and directly furnish the desired amino group. This latter modification is carried out according to the conditions of the Schmidt reaction.

Carbamyl represents another functional derivative of a carboxylic acid, which may be converted to an amino group, for example, according to the Hofmann degradation reaction. This reaction involves bromination of the carbamyl group and rearrangement of the brominated carbomyl group in the presence of an alkali metal hydroxide. The rearrangement leads to an isocyanato group, which is then degraded in the presence of water to the desired amino group.

Other functional groups, capable of being converted to the desired amino groups, are halogeno groups, e.g. bromine and the like. Such groups, present in the piperidino moiety of bis-1-piperidino-alkanes, may be converted to amino groups by treatment with ammonia or an amine, advantageously at an elevated temperature and/or under pressure. Furthermore, such halogen may be exchanged by a primary amino group by way of the Gabriel reaction, i.e. treatment with an alkali metal, e.g. potassium, salt of phthalimidine and hydrolysis of the N-substituted phthalimidide derivative.

Also convertible into compounds of the present invention are bis-(1-pyridinium)-alkane compounds, in which the pyridinium nucleus contains a nitro group; such conversion may be carried out under the conditions used for the reduction of the bis-(amino-1-pyridinium)-alkane derivatives by simultaneously reducing the pyridinium nucleus and the nitro group. Whenever the reduction is carried out in the presence of an aldehyde, e.g. formaldehyde, or a ketone, e.g. acetone, resulting bis-(1-piperi-

11

dino)-alkanes may then contain secondary or tertiary amino groups in the piperidyl moiety.

Previously-described bis-(1-piperidino)-alkane compounds, which contain N-acylamino groups in the piperidino moieties, may also be used for the preparation of the desired bis-(amino-1-piperidino)-alkane derivatives; the hydrolysis may be carried out as previously described. These bis-(N-acylamino-1-piperidino)-alkanes may be obtained by treating a reactive ester of a bis-hydroxy-alkane, in which the hydroxyl groups are separated by at least four carbon atoms, for example, a bis-dihalogeno-alkane, e.g. a bis-bromo-alkane, with an (N-acylamino)-piperididine. The resulting compounds may then be hydrolyzed to the amino derivatives according to previously-described procedures.

The compounds of the present invention may also be obtained by reacting a bis-amino-alkane, in which the amino groups are separated by at least four carbon atoms, with a reactive ester of a 1,5-dihydroxy-pentane, such as a 1,5-dihalogeno-pentane, e.g. a 1,5-dibromo-pentane, which contains, in addition to the ester groupings, an amino group; this reaction, in which piperidino-nuclei are formed, may be carried out according to known conditions.

Compounds of this invention, which have the previously-given formula

in which Alk has the above-mentioned meaning, and the two radicals Pi and Pi' are amino-1-piperidyl radicals, but of different structure, may be obtained, whenever the starting materials are prepared stepwise.

What is claimed is:

1. A member of the group consisting of compounds of the formula:

in which Alk represents alkylene separating group Pi from group Pi' by four to twenty carbon atoms, and each of the groups Pi and Pi' stands for a member selected from the group consisting of 3-amino-1-piperidino, 4-amino-1-piperidino, 3-(N-acylamino-1-piperidino) and 4-(N-acylamino)-1-piperidino, in which acyl represents the acyl radical of an organic carboxylic acid selected from the group consisting of O-lower alkyl-carbonic acid, O-phenyl-lower alkyl-carbonic acid, lower alkane carboxylic acid, trifluoroacetic acid, benzoic acid and phenyl-lower alkanoic acid, therapeutically acceptable acid addition salts thereof, quaternary ammonium hydroxides thereof, lower alkyl quaternary ammonium halides there-

12

of and lower alkyl quaternary ammonium sulfonates thereof.

2. Compounds of the formula:

in which Alk' represents an alkylene radical containing from six to fourteen carbon atoms and separating the two groups Pi₁ by four to fourteen carbon atoms, and Pi₁ represents 4-amino-1-piperidino.

3. Compounds of the formula:

in which Alk'' represents an alkylene radical containing from eight to twelve carbon atoms and separating the two 4-amino-1-piperidino groups by the same number of carbon atoms.

4. 1,8-bis-(4-amino-1-piperidino)-octane.

5. 1,9-bis-(4-amino-1-piperidino)-nonane.

6. 1,10-bis-(4-amino-1-piperidino)-decane.

7. 1,10-bis-(4-amino-1-piperidino)-decane tetrahydrochloride.

8. 1,10-bis-(4-amino-1-piperidino)-undecane.

9. 1,12-bis-(4-amino-1-piperidino)-dodecane.

10. Process for the preparation of a compound of the formula:

in which Alk represents an alkylene radical separating group Pi from group Pi' by four to twenty carbon atoms, and each of the groups Pi and Pi' stands for a member selected from the group consisting of 3-amino-1-piperidino and 4-amino-1-piperidino, which comprises contacting a compound, in an inert solvent, of the formula:

in which Alk has the above-given meaning, each of Py and Py' represents a member selected from the group consisting of 3-amino-1-pyridino and 4-amino-1-pyridino, and An stands for the anion of an acid, with an alkali metal borohydride reducing agent.
